ELECTRIC DRIVE FOR SEWING MACHINES
 Ernst Becker, Darmstadt, Germany, assignor to
 Firma Quick-Rotan Becker & Co.
 Filed Aug. 14, 1962, Ser. No. 216,904
 Claims priority, application Germany, Aug. 16, 1961,
 Q 665
 16 Claims. (Cl. 112—220)

The problem which the present invention seeks to solve is principally that of ensuring that, in a chain stitch sewing machine, the looper can be automatically withdrawn from the last needle loop formed, when this is necessary at the end of a seam, thereby permitting the sewn article to be taken off the machine. This requirement necessitates the provision of means for turning back the mainshaft of the sewing machine through a small given angle at the end of a seam in such manner that the looper will be retracted from the needle thread loop. At the same time, the arrangement must ensure that the needle is clear of the fabric, when the sewing machine has thus been turned back. Finally, it is desired that the reverse rotation and stopping of the machine should be more rapidly effected than can be done by hand. Moreover, it must also be possible for the machine to be stopped, when required, without reverse rotation. The drive means must, therefore, be so contrived that, optionally, the sewing machine can be brought to a stop without previous reversal or after previous reversal, the machine stopping in both instances with the needle in a particular predetermined position which should be always the same.

For solving this problem, the present invention proposes electric drive means for sewing machines, particularly chain stitch sewing machines, comprising a high speed principal drive, a reduced speed drive and a slow speed drive and electric control means which, by reference to electrical switching pulses impressed upon them, cause the sewing machine to be driven by the several drives in a predetermined sequence, the slow speed drive being either a reverse speed drive or a creep speed forward drive, and the switching sequence being so arranged that the reduced speed drive will operate before the main drive takes over when starting and that the reduced speed drive will operate before the slow speed drive brings the machine to a stop.

It has been found that, with a three-stage sewing machine drive, because each stage defines a precisely defined rotary speed at which the machine will be driven, it is possible, by electrical control means, to ensure that the sewing machine shaft can always be rotated back from the same angular position through a precisely predetermined angular distance before stopping. The time required for stopping is appreciably shorter than is possible when turning the machine back by hand. A sewing machine drive, according to the invention, which includes a slow speed reverse drive, operates by driving the machine at high speed, when the main switch is depressed, whereas the reduced speed drive becomes effective, when the button is released, causing the machine to slow down to a reduced speed of revolution and to stop in an axially predetermined position, when the reduced speed drive is disengaged. If the sequence of operations includes the use of a slow speed reverse drive, then this slow speed drive is actuated, when the reduced speed drive cuts out. The slow speed reverse drive turns back the machine from a given predetermined initial position of the mainshaft into an exactly predetermined angular position. The angle through which the mainshaft is turned in reverse is always the same because the slow speed drive always turns back the mainshaft from the same initial position.

Since, when starting the machine, the reduced speed drive is actuated before the high speed drive becomes effec-

2

tive, it is possible to ensure that even the shortest pulse-like depression of the main switch will always cause the machine to be driven by the reduced speed drive before it is stopped and the stopping position to be the same in any circumstances. It is thus possible to induce the machine to sew only a single stitch and to stop in the required predetermined angular position by briefly touching and depressing the main switch.

Conveniently, the torque is transmitted to each individual drive through a separate clutch, and it is an advantage if this torque is derived from a single motor, although naturally the three drives would each be associated with their own driving motor.

In a preferred form of construction of the invention, the reduced speed drive and the slow speed drive both operate on the same shaft carrying a worm through which the torque is transmitted to a driving plate frictionally engageable by a clutch plate. Each of the transmissions providing the reduced speed and the slow speed drive is associated with a brake which can be actuated only when both drives are inoperative and which are both inoperative when only one of the drives is in operation.

In the preferred embodiment of the invention, the reduced speed drive, slow speed drive and principal drive are electromagnetically actuatable. Conveniently, the electric control means comprise a circuit for controlling the reduced speed drive and the slow speed drive as well as a circuit for controlling the magnetically operable clutch plate. A switch is also provided which operates to energise the circuit for the supplementary drives first and then the circuit for the main clutch plate. With advantage, the switch contact associated with the supplementary drives is controlled through a relay equipped with a holding contact for actuating the clutch magnet of the reduced speed drive and the slow speed drive.

In many instances, it may be desirable to provide a two-stage single switch control. If this is done, operation of the switch by partially depressing the foot pedal may be arranged first to start the reduced speed drive for forward running of the sewing machine at a reduced speed (of say 600 r.p.m.). Sewing may be continued at this speed for as long as desired. However, if the foot pedal is then fully depressed, the electromagnetic clutch plate is shifted into engagement with the continuously revolving flywheel, causing the machine to be driven at full speed. At this high speed, sewing can then likewise continue for as long as desired. If the foot pedal is released, the shift magnet of the clutch plate is deenergised first, releasing the clutch from the flywheel. The clutch plate is then urged into frictional contact with the driving plate of the supplementary drives and driven through the reduced speed drive to revolve for instance at a speed of 600 r.p.m. As soon as the clutch plate has accepted this speed of rotation, the slingspring interrupter deenergises the relay controlled by the switch, causing the reduced speed drive to disengage the driving plate.

In order to permit the slow speed drive to fulfil its intended function, it is advisable to comprise four electrically connected slingsprings in the slingspring interrupter assembly. The slingspring which serves for feeding the current is a complete ring without a gap, whereas the three other rings each have an insulating gap, two of them being associated with the holding contact of the relay, whereas the third is connected with a third supplementary contact likewise associated with the relay. This supplementary contact energises the shift magnet of the slow speed drive through an auxiliary relay, when the main relay is de-energised. According to another useful feature, a selector switch may be provided for optionally connecting the holding contact with one of the other slingsprings. This permits the sewing machine to be selectively stopped in a position in which the needle is either fully raised or fully lowered.

Operation of the selector switch may also determine whether the sewing machine is to be turned back after stopping. This will be the case when the selector switch is in one of its end positions. The sewing machine will then stop, when the main switch has been released, in a position in which the sewing needle is clear of the sewn material, permitting the latter to be easily removed from the machine. By placing the selector switch into its alternative end position, the reverse drive can be inactivated. The sewing machine will then stop in the position from which the reverse drive otherwise turns back the main-shaft of the machine.

Instead of being used for driving a chain switch sewing machine which it is desired to bring to a final stop after it has been turned back, the proposed drive means comprising the essential features of the invention may also be used for driving any kind of sewing machine required to stop in an extremely accurately determined position. In such a case, the slow speed drive is not arranged to be a reversing drive but a forward rotating creep speed drive. Conveniently, a reduction gearing may then be included in the transmission between the drive formerly constituting the reverse speed drive and the motor shaft.

If the drive means is used for the precision determination of the stopping position of the main-shaft of the sewing machine, then suitable arrangements are provided for ensuring that the creep speed drive will always take over from the reduced speed drive as soon as the latter is inactivated. To this end, the relay contact which controls the auxiliary relay is permanently connected with the slipring formerly associated with the reverse speed drive. In such an arrangement, the selector switch merely selects the position in which the sewing machine will stop; in other words, the selector switch determines whether the stopping position is with the sewing needle up or down.

In order to reduce the current carried by the sliprings and thus to prolong their life, it is advisable to substitute transistors for the principal and the auxiliary relay.

Moreover, in a further development of the invention, the main switch may be replaced by a photoelectric switching device. The drive means can then be advantageously used for the performance of fully automatic sewing operations. To this end, the sewing machine and its drive means may be associated with a table feed which derives slow motion from a supplementary motor drive. When the required position determined by the photoelectric device has been reached, the sewing machine is started up at full speed. When the required final position is reached, the supplementary drive including the principal drive are rendered inoperative.

Moreover, for automatically starting and stopping the sewing machine, it is advisable to operate the presser foot of the sewing machine by means of a magnet and to control the same by the main switch. Furthermore, the sewing machine may be equipped with a yarn cutting device for cutting off the chained threads between consecutive sewn articles, said cutting device being controlled by the slipring interrupter. To this end, an additional slipring may be provided for controlling the operation of the cutting device. Finally, the circuit which controls the clutch plate shift magnet may include switch means associated with a yarn tension monitoring means.

Other features and advantages of the invention will be described by reference to two embodiments of the invention illustrated in the accompanying drawings in which:

FIGURE 1 is a sewing machine drive comprising a main drive, a reduced speed drive and a slow speed drive;

FIGURE 2 is the bearing mount of the motor including the clutch, the supplementary drives being omitted;

FIGURE 3, is a circuit diagram for controlling the motor in an arrangement according to FIG. 1;

FIGURE 3a shows a main switch in the form of a two-stage switch;

FIGURE 4 is a sewing machine precision drive,

FIGURE 5 is part of the electric circuit associated with the slipring interrupter in one arrangement according to FIG. 4,

FIGURE 6 is a modification of the electrical circuit in transistorized form, and

FIG. 7 is an enlarged sectional view of one of the magnetic clutches, specifically magnetic clutch 19, as seen from the right in FIG. 1.

10 The motor illustrated in FIG. 1 is intended for driving a chain switch sewing machine. The electric motor 1 drives a flywheel 2 engageable by a clutch plate 3 which is connected with a driving pulley 4 for driving the sewing machine 5. Clutch plate 3 can be axially shifted by 15 means of a magnet 6 built into the bearing box of motor 1 between clutch plate 3 and driving pulley 4.

The winding of magnet 6 is fixed. In other words, it is stationary. The armature 8 of the magnet is capable of limited axial shift. When magnet 6 is energised, driving pulley 4 and its shaft and clutch plate 3 are shifted 20 towards flywheel 2 contrary to the pressure of spring 9, that is to say, according to FIG. 1, to the left. This couples clutch plate 3 with the continuously revolving flywheel 2. Driving pulley 4 will then drive the sewing machine at a speed corresponding with say 6000 stitches per minute. If the magnet is de-energised, spring 9 causes clutch plate 3 to engage a brake disc 10 which also serves as a driving plate. If the brake disc is stationary, the sewing machine will be stopped immediately.

25 Brake disc 10 is rotatable and can be driven by a worm 12 and worm wheel 11. The shaft of worm 12 runs in ball bearings 13 and 14 in the casing of motor 1. The free ends 15 and 16 of the worm shaft carry friction discs 35 17 and 18 respectively. The latter are likewise axially shiftable within narrow limits. Friction disc 17 is engageable by a magnetic clutch 19 and friction disc 18 by a magnetic clutch 20 driven by associated drive means. Magnetic clutch 19 revolves at high speed. It is driven by a belt 21 from a driving pulley 24 on the shaft 40 26 of motor 1. In analogous manner, magnetic clutch 20 is driven by a belt 22 from a driving pulley 25 on shaft 26 (FIG. 1). The two transmissions are adapted to drive the worm 12 through the magnetic clutches in opposite directions. Friction disc 17 can be braked 45 by a stationary magnetic brake 27, whereas friction disc 18 can be braked by a stationary magnetic brake 28.

In FIG. 7, is shown an enlarged sectional view of the magnetic clutch 19 and associated components; inclusive of worm 12 and its worm shaft, ball bearing 13, free 50 end 15 of the worm shaft, friction disc 17, magnetic clutch 19, belt 21, and stationary magnetic brake 27. The clutch element 19 is mounted for rotation on the worm shaft carrying worm 12 and is driven by belt 21. Friction disc 17 is rigidly connected to the worm shaft 55 and cooperates with the magnetic clutch 19 to form the clutch element.

The magnetic clutch contains a coil, the beginning of which is taken to a slip ring and the end of which is connected to another slip ring. The brushes used as 60 current supply means slide over these slip rings, the brushes being connected to a current supply. The stationary housing of the assembly contains stationary magnetic brake 27 and this brake contains another coil, one end of which is connected to the negative pole of a rectifier while the other end is connected to the winding of a 65 of the other stationary brake 28 and also to rest contact 33'. When the coil within the magnetic clutch 19 is energized, friction disc 17 is moved to the right and is connected to magnetic clutch 19, wherefore the worm shaft and worm 12 are driven. When the coil within the stationary magnetic brake 27 is energized, friction disc 17 is moved to the left and is braked at the stationary magnetic brake 27.

The circuit diagram illustrated in FIG. 3 is intended 70 for single-switch control. When foot pedal 29 is de-

pressed, an electrical connection is established between the positive pole and contact 30. Consequently relay 31 and the winding of magnet 6 are energized. Relay 31 operates contacts 32, 33 and 34. When contact 33 is closed, the winding of magnetic clutch 19 of the reduced speed drive is energised.

The arrangement is such that the combined response times of relay 31 and magnetic clutch 19 are shorter than the response time of magnet 6. This ensures that depression of foot pedal 29 causes the winding of magnetic clutch 19 to be energised before magnet 6 is energised. Even an abrupt closure of the switch of foot pedal 29 followed by immediate release will thus still ensure that the sewing machine needle will stop in the required position. A sudden depression and release of foot pedal 29 may, in some instances, not even shift clutch plate 3 towards the flywheel 2 at all. This will therefore merely be briefly driven through brake disc 10 by the reduced speed drive.

If, in this single-switch control, foot pedal 29 is not immediately released after having been depressed, then magnet 6 will be activated after the previous energisation of the winding of magnetic clutch 19 and cause clutch plate 3 to be shifted into engagement with flywheel 2 so that the sewing machine will be driven at normal speed in forward direction.

When foot pedal 29 is released, clutch plate 3 will move into engagement with the forward running brake disc 10, causing the sewing machine to be braked to reduced speed. Relay 31 continues to hold via holding contact 32 until the holding circuit is broken by a slip ring interruptor working in conjunction with condenser 24'. The capacity of condenser 24' is suitably chosen to prevent it from supplying relay 31 with power when the synchroniser interrupts the current supply so that at the reduced speed relay 31 will release. The reduced speed drive is thus disconnected at its reduced speed of rotation in a preselected needle position, for instance when the sewing needle is down ("bottom" position). Rest contact 33' is responsible for energising the winding of stationary magnetic brake 28 in slow speed drive. The sewing machine is thus stopped with the sewing needle in lowered position.

If it is desired to stop the sewing machine in such manner that the looper is withdrawn from the last formed needle loop, foot pedal 29 is depressed and at the same time a selector switch 36 operated. This switch is located close alongside the pedal. The selector switch is so contrived that when operated it disconnects the holding contact 32 from a slipring 40, and connects it with a slipring 41. Selector switch 36 is incidentally suitably placed to be actuated by the operator slightly shifting his foot to one side when depressing the pedal. When this is done, the sewing machine will be automatically stopped by reference to slip ring 41. The stopping of the machine is exactly as if the selector switch had not been pushed excepting that the machine will now stop in a different position of the needle. As soon as relay 31 releases and the windings of stationary magnetic brakes 27, 28 are activated, contact 34 of relay 31 is likewise closed. This causes a relay 37 to operate. Relay 37 switches a contact 38 to energise shift magnetic clutch 20 in slow speed drive and simultaneously to inactivate the brakes in the reduced speed drive and slow speed drive. The slow speed drive will therefore now drive brake disc 10 contrary to the previous hand of rotation. In other words, the sewing machine shaft will be slowly rotated in reverse. As soon as rotation has proceeded through the desired angle in reverse, the brush associated with a slipring 42 rides on to the insulating segment, deenergizing relay 37 and reenergising the windings of stationary magnetic brakes 27, 28. The sewing machine will now finally stop in the intended position.

Activation of relay 31 and of magnet 6 may alternatively be effected by a two-stage switch (FIG. 3a).

If, in this latter case, foot pedal 29 of the sewing machine is only half depressed, contact 30' is first closed, causing relay 31 to operate. Relay 31 closes contacts 32, 33 and 34. As soon as contact 33 closes, magnetic clutch 19 in the reduced speed drive is energised. Consequently, friction disc 17 is shifted by magnetic clutch 19, engaging the drive. The sewing machine will therefore now be driven forwards through the worm gearing at reduced speed, say at 600 r.p.m.

If foot pedal 29 is then fully depressed, voltage will be applied to magnet 6 via a contact 35, causing clutch plate 3 to engage the high-speed flywheel 2. The sewing machine will therefore now run at high speed, say 6000 r.p.m.

The procedure for stopping the machine is exactly the same as when a single switch control is provided.

The described drive permits the sewing machine to be started at low speed in the forward direction by half way depression of the foot pedal, the machine running at full speed when the pedal is fully depressed, whereas, by release of the foot pedal, the machine will be stopped automatically with the needle in a prescribed position, say fully "down." If the selector switch 36 is depressed simultaneously with the depression of the foot pedal, the stopping action is as already described, excepting that the machine will stop with the needle in a different position. If stopping of the machine is controlled by slip ring 41, the reverse drive is automatically activated and the sewing machine shaft turned back from a given initial position and then stopped after having rotated back through a given angle. The initial position for reverse rotation is so chosen that the looper will definitely cast off the needle thread loop. The switching times of the reduced speed drive and of the reverse drive are so short that the entire operation is practically instantaneous.

The motor illustrated in FIG. 4 differs from the motor in FIGS. 1 to 3 only in that a pulley 39 is driven through intermediate reduction gearing of say 10:1. The slow speed drive thus becomes a creep drive. The reduction is such that, when driven by the principal drive, the machine will do 6000 r.p.m., when driven by the reduced speed drive it will make 600 r.p.m. whereas when driven by the creep drive its speed will be only 60 r.p.m. The object of the creep drive is merely to rectify the error in position caused by the reduced speed drive. Consequently, slipring 42 is provided with a contact segment only in the region of the angular error due to the reduced speed drive. The creep drive turns the shaft of worm 12 in the same direction as the reduced speed drive.

The electrical circuit associated with the motor, according to FIG. 4, agrees with the circuit associated with the motor shown in FIGS. 1 to 3 excepting that the connection between slipring 43 and contact 34 is permanent. The association of a supplementary contact with selector switch 36 may be dispensed with because the sewing machine is always finally stopped by the creep drive. When providing a creep speed drive of only 60 r.p.m., the possible deviation of the actual stopping position from the required stopping position is small enough to be negligible. The sewing machine will in fact stop exactly in the desired angular position of the machine shaft. The delay involved in having a creep speed is so slight that it is more than compensated by the higher sewing speed in the primary stage. The described arrangement is thus the first which is capable of reducing the angular stopping error to within extremely fine limits without any increase in the necessary stopping time.

In order to reduce the current passing through the sliprings, the circuit may be transistorised in the manner shown in FIG. 6. The synchroniser through which magnetic clutch 19 is energised is located in the base circuit of a transistor 43'. As soon as the brush rides on to the insulated segment of the synchroniser, the windings of magnetic clutch 19 are de-energised. Through microswitches 44 and 45, the latter operates the contacts pre-

viously operated by relay 31. A tuning condenser 46 is placed in series with the winding of magnetic clutch 19 across the transistor. Together with this magnetic clutch 19, the condenser constitutes an oscillatory circuit. When the synchroniser rotates at high speed, tuning condenser 46 prevents de-energisation of magnetic clutch 19. Not until a given speed is reached will the condenser discharge sufficiently to permit magnetic clutch 19 to be de-energised. In other words, the response of the synchroniser at a given speed is determined by the tuning condenser 46. The micro-switches 44 and 45 do the work of the relays 31 and 37 in the embodiment according to FIGS. 1 and 4. The replacement of the relays by the transistors reduces the power the synchroniser is called upon to interrupt. Furthermore, micro-switches controlled by the magnet windings can handle greater power than the relays.

The friction discs 17 and 18 are double-acting and function, on the one hand, as driving discs and, on the other, as brake discs. For transmitting the torque to the worm shaft, they are connected with the magnet housings which are permanently driven by belts 21 and 22, whereas, for braking, they are shifted into engagement with the stationary magnet brake. To this end, they need be shifted through only a small distance. When the supplementary drives are braked, the brake of the reduced speed drive is always activated at the same time as the brake of the reverse running or creep speed drive. Since the time constants of both brake magnets are the same, and this braking effort is twice that of a single brake, the braking effect is substantially greater than in equipment hitherto known, although the times required are the same in both instances. The accuracy of operation is therefore greatly improved for this reason alone.

The mechanical construction of the arrangement is the same as that in the embodiment according to FIGS. 1 and 4, apart from the transmission of torque to the creep speed drive. In the one case, this drive is derived directly from the motor shaft and, in the other, through the intermediary of a special intermediate transmission. The electrical circuit associated with the motor is the same in both cases, excepting that, in one instance, the reversing drive is activated by reference to the position of the selector switch, whereas in the other case, the creep drive is always used.

What I claim is:

1. Drive mechanism for a sewing machine comprising, a motor including a drive shaft having opposite output ends, a primary high speed drive including a rotatable flywheel mounted on one of the output ends of the drive shaft of said motor and a rotatable clutch plate engageable by said flywheel and a rotatable driving pulley interconnected with said clutch plate and a rotatable brake disc/driving plate, the brake disc/driving plate and flywheel and clutch plate of said primary high speed drive being coaxial, the clutch plate of said primary high speed drive being axially shiftable between the flywheel and brake disc/driving plate thereof, a worm wheel-worm-worm shaft subassembly for driving the brake disc/driving plate of said primary high speed drive, a pair of auxiliary drives including a reduced speed drive and a slow speed drive, said reduced speed drive constituted by a rotatable friction disc on the worm shaft of said worm-wheel-worm-worm shaft subassembly and a rotatable magnetic clutch engageable with the friction disc and driven by a drive from the opposite output end of the drive shaft of said motor and a stationary magnetic brake, the magnetic clutch and friction disc and magnetic brake of said reduced speed drive being coaxial, the friction disc of said reduced speed drive being axially shiftable between the magnetic clutch and magnetic brake thereof for selectively rotating the worm shaft in a certain direction of rotation, said slow speed drive constituted by a rotatable friction disc on the worm shaft of said worm-wheel-worm-worm shaft subassembly and a rotatable magnetic clutch engageable with the friction disc and driven

by a drive from the said opposite output end of the drive shaft of said motor and a stationary magnetic brake, the magnetic clutch and friction disc and magnetic brake of said slow speed drive being coaxial, the friction disc of said slow speed drive being axially shiftable between the magnetic clutch and magnetic brake thereof for selectively rotating the worm shaft in a direction of rotation opposite to said certain direction of rotation, the said opposite output end of the drive shaft of said motor being a common power output to said reduced and slow speed drives for driving the worm shaft successively in opposite directions of rotation through the respective auxiliary drives of said pair thereof.

2. Drive mechanism according to claim 1 having a single control switch for machine starting and stopping.

3. Drive mechanism according to claim 2, in which the three separate clutches are driven by said motor.

4. Drive mechanism according to claim 3, with the magnetic brakes of said reduced speed and slow speed drives each being operable only when both of said drives are rendered inoperative and being jointly released when only one of said drives is operational.

5. Drive mechanism according to claim 4, in the clutch discs of said reduced speed and slow speed drives each being electromagnetically operable by electric control means including a main switch for first applying a potential to a circuit controlling the drives through a first switch contact and then to a circuit controlling the drives through a second switch contact.

6. Drive mechanism according to claim 5, the first switch contact being associated with a relay having a holding contact for energizing a shift magnet of said reduced speed drive and a shift magnet of said slow speed drive.

7. A drive according to claim 6, said relay in the control circuit of the auxiliary drives of said pair thereof having a contact which, for establishing upon relay energization a connection between the shift magnet of said reduced speed drive and the current source and for establishing upon relay de-energization a connection between the brake magnets associated with said reduced and slow speed drives.

8. Drive mechanism according to claim 7, having a slipping interrupter comprising four conductively connected slippings, the slipping connected with the current supply being without a gap and the other slippings being with a gap, two of the latter being associated with the holding contact of said relay whereas the third precedes a further switch contact associated with said relay arranged to energize the shift magnet of the slow speed drive through a supplementary relay when said relay is de-energized.

9. Drive mechanism according to claim 8, including a selector switch adapted to connect the holding contact of said relay selectively with either one slipping or the other.

10. Drive mechanism according to claim 9, said selector switch comprising the switching element for permitting the supplementary relay for the slow speed drive to be connected with and disconnected from a slipping according to the position of selector switch position.

11. Drive mechanism according to claim 10, including a reduction gearing interposed between the drive shaft of said motor and said slow speed drive.

12. Drive mechanism according to claim 11, in which a winding of the shift magnet for the clutch plate is fixed in a bearing box and the magnet armature is fast with the shift sleeve, the winding being cylindrical and embracing the shift sleeve.

13. Drive mechanism according to claim 12, in which the driving disc is mounted on a hub connected with the bearing box and is of integral construction with the worm-wheel, said hub also supporting the shift sleeve on the output side of the clutch.

14. Drive mechanism according to claim 13, in which the main switch is operable by a foot pedal in such manner that partial depression of the pedal closes one of the

switching contacts and full depression closes the other switching contact.

15. Drive mechanism according to claim 14, in which the said relay and the supplementary relay are replaced by transistors.

16. Drive mechanism according to claim 15, in which the slipping interrupter comprises a supplementary slipping ring for controlling a yarn cutting device.
